UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SAFETY DEVICE FOR PRESSES.

1,167,476.

Specification of Letters Patent.

Patented Jan. 11, 1916.

Application filed July 3, 1913. Serial No. 777,372.

To all whom it may concern:

Be it known that I, REUBEN B. BENJAMIN, a citizen of the United States, residing at Chicago, in the county of Cook and State 5 of Illinois, have invented new and useful Improvements in Safety Devices for Presses, of which the following is a full, clear, concise, and exact description, reference being had to the accompanying drawings, forming a part of this specification.

My invention relates to improvements in protective means for presses, and particularly to punch and stamping presses, and the like.

15 It has for its object to provide a barrier which is arranged to be dropped into position during the operation of the press and prevent the operator from placing his hands in a dangerous position, the barrier being 20 arranged to prevent the press from being tripped when raised so that the hands may be inserted in the press.

For the purpose of illustrating my invention I have shown one embodiment there- 25 of in the accompanying drawings, in which—

Figure 1 is a side elevation of a press having one embodiment of my safety mechanism attached thereto; and, Fig. 2 is a front 30 plan view showing the construction of the barrier.

In the embodiment illustrated, the press 1 may be of the usual construction having a reciprocating ram which is operated in the 35 usual manner and which is provided with a tripping mechanism 2 of the usual construction. This tripping mechanism is connected with a pivoted lever 3 by a rod 4. The pivoted lever is also pivoted by a rod 5 with 40 a foot lever 6 arranged on the right hand side of the press, the construction being such that when the lever is depressed by the operator's foot the press will be tripped.

On a portion of the frame of the press I 45 mount a framework 7, which is provided with slots 8 through which the securing bolts 9 are adapted to be passed, whereby the framework may be adjusted vertically, and at the lower end of this frame I provide 50 a shaft 10 on which is rigidly mounted a barrier 11, which barrier is adapted to drop down on the press in a position immediately above the table 12 thereof and in front of the operating mechanism of the 55 press. This barrier is slotted as at 13, so

that the operator may see therethrough, or may take any form of a visual barrier, such, for instance, as a screen or a piece of glass or any other structure. On the left-hand side of the shaft 10 I provide a crank arm 60 14 which at its outer end is connected by a rod 15 with a lever 16 pivoted at 17 to the press. By depressing the outer end of the lever 16 the rod 15 will be raised, thereby rocking the barrier inwardly and toward a 65 horizontal position. The barrier is connected by a rod 18 with a pivoted stop 19, arranged when the barrier is in its raised or horizontal position to be swung in the path of the lever 3 so that the tripping mechanism of the press cannot be operated.

In operation, the operator by his left foot first depresses the lever 16, whereby the barrier 11 is swung inwardly and upwardly to permit the work to be inserted in the press. 75 At the same time the stop 19 is swung in the path of the lever 13 so that the press cannot be tripped. When the operator has placed the work in the press and removed his hands he then releases the lever 16, which permits 80 the barrier to swing back to normal position and in a position to prevent the hands from being inserted in the press, and by depressing the lever 3 with his left foot trips the press. It will be noted that as long as the 85 barrier is raised for the insertion of the hands in the press the press cannot be tripped, and it will also be noted that the barrier cannot be permitted to fall back into its normal position until the hands are removed.

In some instances I may dispense entirely with the lever for operating the barrier and depend merely upon the operator raising the same by pushing his hands against the barrier when inserting the work in position. This operation, however, would throw the stop 19 into the path of the lever 3 and prevent the tripping of the press as long as the barrier was raised.

Having thus described my invention, what I claim as new and desire to secure by Letters Patent is—

1. In a safety device for presses, the combination with a movable member for tripping the press, of a barrier pivoted in front of the operating mechanism of the press and arranged when in closed position to prevent the operator from inserting his hands in the operating mechanism of the press and to be 110

swung on its pivot to a substantially horizontal position to permit the insertion of the work in the mechanism of the press, and means connected with said barrier arranged to be moved in a locking position to prevent the tripping of the press when the barrier is swung to open position.

5. In a safety device for presses, the combination with a movable member for tripping the press, of a barrier pivoted above the table of the press and arranged to hang in a substantially vertical position in front of the operating mechanism of the press and to be swung on its pivot toward a horizontal position to permit insertion of the work in the operating mechanism of the press, and means connected with said barrier arranged when the barrier is swung in a horizontal position to lock the movable tripping member against movement.

10. In a safety device for presses, the combination with a movable tripping member for the press, of operating means for said tripping member, a barrier pivoted in front of the operating mechanism of the press and arranged to be swung to a substantially horizontal position to permit the insertion of the work in the press, and a stop connected with said barrier and arranged to be moved into position to prevent said operating means from moving said movable member when the barrier is swung to substantially horizontal position.

15. In a safety device for presses, the combination with a movable member for tripping the press, of a barrier pivoted in front of the operating mechanism of the press and arranged when in closed position to prevent the insertion of the hands in the mechanism of the press, said barrier being arranged to be swung to a substantially horizontal position to permit the insertion of the work in the mechanism of the press, and means connected with said barrier arranged when 20 the barrier is swung to horizontal position to be thrown into locking position to prevent the tripping of the press, said means remaining in locking position until the barrier is returned to full closed position.

25. In a safety device for presses, the combination with a spring-returned tripping mechanism, of a pivoted arm, a rod connecting said tripping mechanism with said arm, means for depressing said arm, a stop, a barrier pivoted above said press and arranged to be swung toward horizontal position to permit the work to be inserted in the operating mechanism of said press, and means connecting said barrier with said stop for moving said stop into the path of said pivoted arm when the barrier is swung to permit the insertion of the work in the press.

30. In a safety device for presses, the combination with a tripping mechanism for the press, to a pivoted arm, means connecting

said mechanism with said arm, a barrier pivoted above the table of the press and arranged when in closed position to extend substantially at right angles to the table of the press and arranged to be swung on its pivot to a substantially horizontal position to permit the work to be inserted in the operating mechanism of the press, a stop, and means connecting said stop with said barrier and arranged to move the stop in the path of said pivoted arm to prevent said arm from moving until the barrier is moved to its substantially vertical position.

35. In a machine having a part movable in a definite path, means for controlling the movement of said movable part, in combination with a barrier movable from a substantially vertical toward a horizontal position, which in vertical position hinders the operator from placing his hands in the path of said part, and means for normally holding said barrier in this position.

40. In a machine having a part movable in a definite path, means for controlling the movement of said movable part, in combination with a barrier movable from a substantially vertical toward a horizontal position, which in vertical position hinders the operator from placing his hands in the path of said part, means for normally holding said barrier in this position, and means for controlling said first controlling means controlled by said barrier.

45. A machine having a part movable in a definite path and having means for controlling the movement of said movable part, in combination with a barrier movable from a substantially vertical toward a horizontal position, which in vertical position hinders the operator from placing his hands in the path of said part, means for normally holding said barrier in this position, and stop means for controlling said first controlling means controlled by said barrier.

50. A machine having a part movable in a definite path, in combination with a barrier movable from a substantially vertical toward a horizontal position, which in vertical position hinders the operator from placing his hands in said path, means for normally holding said barrier in said position, and means whereby movement of said barrier from said position controls the movement of said part.

55. A machine having a part movable in a definite path, in combination with a barrier movable from a substantially vertical toward a horizontal position, which in vertical position hinders the operator from placing his hands in said path, means for normally holding said barrier in said position, and means whereby movement of said barrier from said position restricts the movement of said part.

60. A machine having a part movable in a definite path, in combination with a barrier movable from a substantially vertical toward a horizontal position, which in vertical position hinders the operator from placing his hands in said path, means for normally holding said barrier in said position, and means whereby movement of said barrier from said position restricts the movement of said part.

a substantially vertical path, a pivotally mounted guard adjacent said part, means for normally holding said guard in substantially vertical position, means for controlling the movement of said part, a stop member movable into and out of the path of said controlling means, and a link directly connecting said guard and said stop member.

13. A machine having a part movable in
10 a substantially vertical path, a pivotally mounted guard adjacent said part, means for normally holding said guard in substantially vertical position, means for controlling

ling the movement of said part, a pivoted stop member movable into and out of the 15 path of said controlling means, and a link directly connecting said guard and said stop member.

In witness whereof, I have hereunto subscribed my name in the presence of two witnesses.
